TRIPLE ACTION EXPLOSIVE
SHRAPNEL BULLET

Joseph Raymond Palagonia, Ridgewood, N. Y.

Application February 2, 1945, Serial No. 575,762

2 Claims. (Cl. 102—67)

1

This invention relates to new and useful improvements in a bullet.

This application is a substitute of my abandoned application deposited in the United States Patent Office on October 28, 1940.

More specifically, the present invention proposes the construction of a shrapnel explosive, especially an explosive projectile having three projectiles connected together for unitary flight and explosion, each of the projectiles being shrapnel carrying.

Still further, it is proposed to provide a device as aforesaid in which the three projectiles are disposed in the same plane but at right angles to each other, two of the projectiles being aligned and together intersecting and being secured to the other projectile.

Another object is to provide a bullet as aforesaid having a cylindrical projectile acting as the carrying agent for the other projectiles, the other projectiles being streamlined similar to the wings of an airplane to minimize air friction and resistance.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side view of a rifle provided with a bullet constructed in accordance with this invention.

Fig. 2 is an enlarged axial section through the bullet, the rifle barrel being indicated in dot-dash lines.

Fig. 3 is a plan view of a bullet constructed in accordance with a modification of this invention, in flight.

Fig. 4 is an enlarged section on the line 4—4 of Fig. 3 looking in the direction of the arrows.

Fig. 5 is a view similar to Fig. 2 of a bullet constructed in accordance with a further modification of this invention.

Fig. 6 is a view similar to Fig. 2 of a bullet constructed in accordance with a further modification of this invention.

The bullet, according to this invention, comprises a longitudinal shell 10 extending in the proposed direction of flight, and two other shells 11 and 12 disposed at right angles to shell 10 on opposite sides thereof, and being aligned with each other. Shell 10 forms a part of the projectile, and shells 11 and 12 each forms a part of another pro-

2

jectile, there being three projectiles to the bullet.

The projectiles of shells 11 and 12 are similar and each is connected to the shell 10 by having its rear end disposed in an orifice 13 in the shell 10 intermediate its ends. Shells 10, 11 and 12 are preferably securely fastened together, as by welding.

The bullets may be made in any size. For instance they may be made to fit rifles, or they may be made to be used in small cannons such as mortars. In Fig. 1 the bullet is shown assembled with a rifle 14, the rifle being of a calibre such as a .30-30 and having its barrel end 15 enlarged to receive the rear end of the shell 10. The bullet is projected from the barrel by a charge contained in the gun barrel and fired in a conventional way. That is to say, the rifle or cannon, neither of which form a part of this invention, will be adapted to project the bullet therefrom.

20 The shell 10 has a main charge of gunpowder 16 between the orifices 13, that is to say, at a position where it will affect all three projectiles in substantially the same manner.

25 Each shell has a port 17 in its outer end, a firing pin 18 slidably disposed in the port and coacting at its inner end with an explosive charge or device 19 in the nose of the shell, a fuse 20 extending from the device 19 to the main charge 16, and a charge of shrapnel 21 around the fuse 20. Each fuse 20 ends in guncotton 22 adjacent the charge 16.

30 The pin 18, device 19, fuse 20 and guncotton 22 forms a combination fuse, time and percussion mechanism for exploding the main charge 16. 35 Ordinarily the bullet will fire from the pin 17 in the end of the shell 10 and therefore, in some cases if desired, the combination fuse, time and percussion mechanism may be omitted from the shells 11 and 12.

40 Shell 10 also includes a shrapnel charge behind the main charge 16, but if desired this may be omitted and this part of the shell 10 padded with wads of felt and cotton.

45 The bullet is especially adapted for shrapnel shooting from small arms such as infantry rifles or machine guns at close range where aim is of minor importance and shrapnel spread is of major importance. It has been found that a single shrapnel tube is not efficient due to its tendency 50 to over shoot the mark and to pass through the desired area without exploding. The shrapnel bullet of the present invention, provided with the three projectiles at right angles to each other, is devised to explode at its target with more regularity. 55 This is due to the fact that the bullet has an effec-

tive cross sectional area equal to the distance from the tip of shell 11 to the tip of shell 12, it has three firing pins 17, any one of which will explode the bullet, and further because the shells 11 and 12 retard the flight and give the bullet a greater chance of hitting its target and exploding.

The pins 17 may explode the bullet either by contact with the target or some adjacent structure, or they may be part of timing mechanism for exploding the bullet after it has travelled a predetermined distance.

The operation of the bullet is as follows:

The bullet is aimed by means of the rifle and discharged from the rifle by the charge in the rifle. This charge may be separate from the bullet or may be contained in a shell connected to the shell 10 similarly to the way a shell is connected to a solid metal .30-30 rifle slug.

The bullet, after being discharged, travels to its target, which upon being hit, actuates the pin 17 of shell 10 to explode the device 19, set the fuse 20 afire, and then the guncotton 22, whereupon the main charge 16 is exploded. The main charge 16, on exploding, shatters the shells 10, 11 and 12, scattering their shrapnel charge. Thus the bullet has a heavy shrapnel spread in comparison with the calibre of the shell 10.

Should the bullet miss its target, or be deflected by some object, the shells 11 and 12 would tend to whirl the bullet, causing it to hit something near the target. In this way, the chance of one of the three pins being actuated is very good and thus the bullet has a maximum chance of exploding at or near its target. Furthermore, as the three shells are directed in three different directions, the shrapnel has a tendency to cover a larger area than it would if it were all stored in one shell.

A bullet constructed in accordance with a modification of this invention is shown in Figs. 3 and 4. In the main, it is similar to the bullet of Fig. 1 and like parts are designated by like references with an accent added. The modified bullet distinguishes from the bullet of Figs. 1 and 2 in that the shells 11' and 12' are elliptical in cross section, as is clearly shown in Fig. 4, this shape streamlining the bullet, the shells 11' and 12' acting as wings, enabling the bullet to soar similar to a jet-propelled rocket projectile.

A bullet of the triple-action type constructed in accordance with a further modification of this invention is shown in Fig. 5. It distinguishes from the bullet of Figs. 1 and 2 in that each of the shells 10'' and 12'' contains an explosive charge 16''. In this form of the invention when the main charge 16'' explodes, it causes shells 12'' to fly each in opposite directions, and hitting objects in their respective areas and also exploding, thus causing damage in three entirely separated areas.

A single action bullet having some of the features of the present invention is shown in Fig. 6. This bullet has the usual powder containing shell 23 adapted to fit in the rear end of a rifle or machine gun barrel. The projectile of this bullet includes a shell 10''', a firing pin 17''', powder 19''', wads 25, and shot 21'''. This bullet is suitable for .30-30, .50 cal., or large calibre, and for 20 mm. It may also be made without the time fuse 20', being operated by the firing pin 17''' only.

While I have illustrated and described the preferred embodiments of my invention, it is to be understood that I do not limit myself to the

precise constructions herein disclosed and the right is reserved to all changes and modifications coming within the scope of the invention as defined in the appended claims.

Having thus described my invention, what I claim as new, and desire to secure by United States Letters Patent is:

1. An explosive projectile comprising a cylinder insertable in a gun barrel and provided with containers extending from opposite sides thereof and disposed at approximately right angles thereto and located inwardly of the forward end of said cylinder, said cylinder having a nose at its forward end provided with a firing pin projecting outwardly thereof, each of the containers having a nose at its outer end provided with a firing pin projecting outwardly thereof and being streamlined in cross section, the whole unit having the general form of an airplane and capable of plane flight when projected, said cylinder being supplied with a shrapnel explosive charge located between the inner ends of said containers each of said containers being supplied with a shrapnel explosive charge at their inner ends adjacent said cylinder, and a fuse extending from each of said firing pins to the explosive charge of the respective cylinder or container.

2. An explosive projectile comprising a hollow longitudinal shell having a nose at its front end, hollow shells extending at right angles from diametrically opposite sides of said longitudinal shell and being in contact with the interior of said longitudinal shell, said hollow shells having noses at their outer ends, a firing pin mounted in each of said noses, an explosive charge mounted in said longitudinal shell between the inner ends of said hollow shells, an explosive charge mounted in each of said hollow shells adjacent the inner ends thereof, fuses extended longitudinally through said shells between said firing pins and the respective explosive charges, said fuses being of a cross-sectional diameter considerably less than the inside cross-sectional diameter of said shells, and shrapnel filling the space about each of said fuses in each of said shells between the adjacent faces of the respective firing pin and explosive charge.

JOSEPH PALAGONIA.
